EYE PROTECTOR

Edgar D. Tillyer and Ercell A. Teeson, Southbridge, Mass., assignors to American Optical Company, Southbridge, Mass., a voluntary association of Massachusetts

Application March 29, 1930. Serial No. 440,027

4 Claims. (Cl. 2-14)

This invention relates to improvements in eye protectors and has particular reference to an improved type of ventilation therefor.

The principal object of this invention is to provide means whereby the amount of ventilation in an eye protector will be substantially constant regardless of the conditions under which said eye protector is used.

Another object of this invention is to provide an eye protector particularly adapted for aviation and other high-speed occupations by having ventilation which is regulated by the velocity of the external air.

Another object of this invention is to provide simple and economical means of automatically reducing or increasing the ventilating air supply.

Other objects and advantages will become apparent from the following description taken in connection with the accompanying drawing and it will be understood that many changes may be made in the details of construction and arrangement of parts without departing from the spirit of the invention as expressed in the accompanying claims. We, therefore, do not wish to be limited to the exact details shown and described as the preferred forms only have been shown by way of illustration.

In the drawing:

Fig. I is a front view of an eye protector embodying the invention.

Fig. II is a fragmentary and enlarged perspective view of the ventilating means showing the parts separated.

Fig. III is a longitudinal sectional view through the improved ventilating means.

Fig. IV is a sectional view taken on line IV—IV of Fig. I.

Fig. V is a sectional view similar to Fig. III but showing a modification.

Fig. VI is a fragmentary enlarged view of the modification shown in Fig. V.

Fig. VII is a fragmentary enlarged view of the tubular member showing a further modification.

Fig. VIII is a section taken on line VIII—VIII of Fig. VII.

Fig. IX is a perspective view of a modified form of vent control means.

Eye-protectors for aviators, automobilists and others engaged in high-speed occupations are usually ventilated by a suction device of some nature which is dependent upon the velocity of the wind and the speed of the machine for its operation. Usually the wind thus created is allowed to pass through a specially designed chamber and to draw as it goes the warm air from the

interior of the eye-protector. It will readily be seen from this operation that an unfortunate condition is present, inasmuch as a device which is quite efficient at slow speeds, by giving sufficient ventilation, will invariably give too much at a higher rate of speed. The converse is, of course, true and if the ventilation is made for a high rate of speed, such as is usual in combat planes, it will be too restricted for use in ordinary transport work.

It is the prime object of our invention, therefore, to provide a ventilating device for these eye-protectors which will regulate the flow of air to the interior of the eye-protector according to the speed at which the user is travelling or the velocity of the wind past his head and keep a constant degree thereof.

Referring to the drawing wherein similar characters of reference denote corresponding parts throughout the several views the numeral 1 denotes the lenses of an eye-protector which are supported by the lens rims 2. The lens rims 2 are joined together by the hinged bridge 3 having struts 4 extending from the hinge-posts 5 for this purpose.

The lens rims 2 are split at their temporal ends and clamped together at this point by means of the endpieces 6 carrying the headband 7.

A face contact member 8 of rubber or other resilient material is fitted into each lens rim 2 and clamped therein by the action of the endpieces 6. A metal frame 9 may be secured to the face contact member 8 by sewing, cementing or other suitable means. The shape of the rubber face contact member is thereby preserved and it may be freely removed and inserted into the split lens rim 2 and clamped more firmly in position. A series of holes 31 in the rim 2 and 30 in the frame 9, Fig. IV, admit air to the interior.

The details of construction set forth in the foregoing may be varied at will as the novel feature of this invention does not depend to any great extent upon the exact arrangement described. The ventilation of the eye-protector has been incorporated into the described embodiment and the novelty of our device will now become apparent together with its adaptability to various types of eye-protector.

Referring more particularly to Figs. II and III the ventilation arrangement consists preferably of a tubular member 10 having within its bore a pair of internally tapered sleeves 11. These sleeves 11 are preferably pressed into the bore from each end with a small space 12 between them. Communication with the exterior is next

provided by slotting the tubular member 10 at one side opposite the space 12 so that air passing through the tapered sleeves will communicate with the air entering through slotted portion between them. To the tubular member 10 and covering the slotted portion we next attach, by soldering or other suitable method, a support member 13 having a hole 14 therethrough. From Fig. III it will clearly be seen that an air passage is provided from the tapered sleeves 11 through the slotted portion of the member 10 to the hole 14. The end of the support 13 may be reduced to enter a hole 15 in the lens rim 2 and the assembled ventilation means may therefore be secured, by soldering or other suitable means, to the said lens rim 2.

The rubber face contact 8 is cut away at the point of connection to form the aperture 16 and a hole 17 is provided in the frame 9 at this point. It will readily be seen that air passing in either direction through the tapered sleeves 11 will suck air from the interior of the eye-protector through the holes and slot communicating therewith.

We have found, however, that the velocity of the air passing through the tapered sleeves 11 is dependent in its suction effect upon the size of the communicating holes in the lens rim 2 and the frame 9.

We have, therefore, utilized this to overcome the serious objections to prior forms of ventilation which have been described herein and to provide an automatic control of the amount and force of the suction draft applied to the interior of the eye-protector.

In carrying out this improvement we provide on the inner frame 9 a thin strip of material forming a tongue 18 which may be attached at one end to the said frame 9 by rivets 19 or other suitable means. The tongue 18 extends along the inner frame 9 and covers the vent hole 17 therein, although at this point it is sloped away from contact therewith. A hole 20 of much smaller diameter than the vent hole 17 is provided in the tongue 18 and is shown in Fig. III opposite said vent hole 17.

The operation of the device is of an extremely simple but very efficient nature inasmuch as when the velocity of the air passing horizontally through the tapered sleeves 11 reaches a certain point the increased suction in the vertical direction through hole 14 will cause the sloping tongue 18 to move towards the vent hole 17 and cling to the frame 9 at this point, thus reducing the size of the vent hole 17, in effect, to that of the hole 20 in the tongue 18.

When the speed of the plane is reduced or the velocity of the wind drops the suction in the ventilation means will correspondingly grow less, whereupon the tongue 18 will automatically return to its normal position and allow the large vent hole 17 to resume its operation and pass a larger quantity of air therethrough.

This hole 20 may be positioned slightly offset from the vent hole 17 as long as some air may pass therethrough. In this connection the modified form of tongue 35 having no hole, as shown in Fig. IX, may also be used. In this embodiment the end is turned up at 36 so that the flat portion will be held spaced from the hole 17 in the frame 9 when the suction causes the tongue to move towards it. The air will thus pass across the eyecup to the hole 17 but not have a clear passage thereto owing to the obstruction of the tongue 35. The air will necessarily circulate around the sides of the tongue member 35 and

due to the turned up edge 36 will be able to flow between the tongue 35 and frame 9 and so through the hole 17 therein. It will be obvious that this modification has precisely the same effect as the previously described embodiment in creating an impedance for the flow of air as soon as the suction is increased.

As a modification we can provide means to accomplish the desired variable ventilation wherein the velocity of the air itself will prevent too much suction being created in the eyecup as distinct from the previously described form wherein the suction was graduated by mechanical means. In this embodiment we provide means to create centrifugal force and turbulence of the air sucked through the ventilation means. Referring to Figs. V and VI, we provide a support member 21 which supports the tubular member 10 over the eyecup. The support member 21 has an extension through the face contact member 8 which fits above the hole 14 in the frame 9. In the bore of the support 21 we provide a preferably helical groove 22 extending from the tubular member 10 to the frame 9 opposite the hole 14 therein.

The air rushing through the tapered sleeves 11, as in the previous case, will cause suction in a vertical direction through the hole 14. When the velocity of the wind through the sleeves 11 is slow the air sucked through the hole 14 passes with little impedance through the center passage 23 of the support 21. However, as the velocity increases the air will be sucked up faster, but owing to the helical groove it will not find a clear passage. The centrifugal force and turbulence created in the helical groove by the increased sucking action of the air velocity, through the tapered sleeves 11, will increase at a very much faster rate than the increase of sucking action due to velocity, so that very little more air will pass through the support 21 from the interior of the eyecup than at slow speeds.

In Figs. VII and VIII a further embodiment of the centrifugal force and turbulence principle has been shown. This embodiment may have the tapered sleeves 11 with a tubular member 10 as before, but without the extension on the support 21. To create centrifugal force to control the amount of air sucked from the eyecup we provide a groove 24 in the face of each taper sleeve 11 at the space 12 between them in the form of an ionic volute. The air is sucked up from the interior of the eyecup by the velocity of the air passing horizontally through the tapered sleeves 11 as in the previous cases. This embodiment, however, depends more upon centrifugal force for the control of the air suction than upon turbulence although the latter enters as a factor. We have found that the centrifugal force tending to keep air away from the center portion of the slot 12 increases as the square of the velocity, so that the amount of air drawn through is not increased a great deal as the suction effect increases.

From the foregoing it will be apparent that we have provided extremely simple means to overcome the objections to prior art ventilating means on eye protector. The ventilation is variable according to the speed at which the wind travels and ample ventilation may be provided at slow speeds without fear of harmful effects when the speed is increased. It will be also apparent that automatic means have been provided to carry out the improvement and the wearer is free to attend

to other necessary operations while the ventilation takes care of itself.

Having described our invention, we claim:

1. In a device of the character described, an eyecup member having an orifice therein through which air may pass, a cover member over the orifice having an oppositely tapered bore, the smaller cross-section of which is intermediate its ends and having an opening which overlies the orifice causing suction of air in the eyecup and a tongue member having an aperture therein overlying the orifice and operated by the said suction to superimpose the aperture over the orifice to change the amount of suction in the eyecup.

2. In a device of the character described, an eyecup having an orifice therein through which air may pass, a member over the orifice adapted to cause suction of the air in the eyecup and a tongue member having an aperture therein overlying the orifice and operated by the said suction to superimpose the aperture over the orifice to change the amount of suction in the eyecup.

25 3. In a device of the character described, an

eyecup having an orifice therein through which air may pass, a member over the orifice having an oppositely tapered bore, the smaller cross-section of which is intermediate its ends and having an opening which overlies the orifice causing suction of air in the eyecup and a tongue member having an aperture therein overlying the orifice and operated by the said suction to superimpose the aperture over the orifice to change the amount of suction in the eyecup.

80

4. In a device of the character described, an eye cup having an orifice therethrough, a member external of the orifice having means for directing air currents across the orifice to cause air to be drawn out through the orifice, and structural means associated with the orifice through the eye cup operable automatically by the passage of the air for maintaining the flow of air from the eye cup through said orifice of substantially constant velocity irrespective of the velocity of the air currents directed across the orifice by the said external member.
